US00D970609S

(12) **United States Design Patent** (10) **Patent No.:** **US D970,609 S**
Staudinger et al. (45) **Date of Patent:** **** Nov. 22, 2022**

(54) **COMBINATION WRISTBAND WITH SLOTS AND LABEL FORM**

(71) Applicant: **Ward-Kraft, Inc.**, Fort Scott, KS (US)

(72) Inventors: **Gina Staudinger**, Louisburg, KS (US); **Phil Quick**, Fort Scott, KS (US); **Roger Kraft**, Fort Scott, KS (US)

(73) Assignee: **Ward-Kraft, Inc.**, Fort Scott, KS (US)

(**) Term: **15 Years**

(21) Appl. No.: **29/778,484**

(22) Filed: **Apr. 13, 2021**

(51) LOC (13) Cl. **19-01**

(52) U.S. Cl.

USPC **D19/1**

(58) **Field of Classification Search**

Primary Examiner — Abraham Bahta

(74) Attorney, Agent, or Firm — Avek IP, LLC

(57) **CLAIM**

The ornamental design for a combination wristband with slots and label form, as shown and described.

DESCRIPTION

FIG. 1 is a front view of the combination wristband with slots and label form; and,

FIG. 2 is a back view of the combination wristband with slots and label form of FIG. 1.

The dash-dot-dot-dash lines in FIGS. 1 and 2 illustrate die cuts that form part of the claimed design. The dashed lines shown in FIGS. 1 and 2 do not form a part of the claimed design.

1 Claim, 2 Drawing Sheets
